UNITED STATES PATENT OFFICE.

JOHN C. RINGE, OF STRATFORD, CONNECTICUT, ASSIGNOR TO THE SINGER MANUFACTURING COMPANY, OF ELIZABETH, NEW JERSEY, A CORPORATION OF NEW JERSEY.

FOLDING MACHINE.

Application filed November 19, 1923. Serial No. 675,508.

To all whom it may concern:

Be it known that I, JOHN C. RINGE, a citizen of the United States, residing at Stratford, in the county of Fairfield and State of Connecticut, have invented certain new and useful Improvements in Folding Machines, of which the following is a specification, reference being had therein to the accompanying drawings.

This invention relates to improvements in folding machines and has for an object to provide a machine of this character which, while capable of other uses, is more particularly designed to effect the folding operation in the method of producing the so-called "French-cord" forming the subject of the U. S. patent to D. Daniels, No. 1,400,806, Dec. 20, 1921.

Other and more specific objects of the invention will be apparent from the following description and claims.

In the production of the "French-cord" of said Daniels Patent No. 1,400,806 a galloon having a corded or thickened edge is secured by a line of stitches to the margin of a body-material such as a shoe-upper, the line of stitches being disposed closely adjacent to the thickened margin of the galloon and between the thickened galloon-margin and said body-material margin. The galloon and the body-material are then folded substantially on the stitch-line, the fold being secured by a cement previously applied. In order to meet commercial requirements, it is essential that a machine designed to effect this folding operation be effective when operating upon sharply curved materials as well as straight edges in order to produce a uniform folded edge.

The present folding machine, in its preferred embodiment, includes a clamp-feeding mechanism for advancing the work past the folding instrumentalities, which comprise a stationary fold-determining member and a movable folder reciprocated in a right line across the free edge of the fold-determining member. At the completion of its folding movement, the folder is disposed directly in advance of the initial work-

engaging position of the upper feeding-foot which is partially cut away to provide clearance for the fold-determining member. The upper feeding-foot acts to complete the folding operation initiated by the folder and yieldingly presses upon the cemented margins whereby they adhere to the reverse side of the body-material. By means of this disposition of the feeding and folding instrumentalities the span of simultaneous engagement of the work thereby is so short as to permit of the turning of very sharp curves, such as are present for instance in shoe-straps.

In the accompanying drawings, Fig. 1 is a longitudinal sectional view of a folding machine embodying the present improvements. Fig. 2 is a top-plan view of the work-cylinder, the fold-determining member, and the feeding foot. Fig. 3 is a front end view of the machine. Fig. 4 is a sectional view substantially on the line $x-x$ of Fig. 1. Fig. 5 is an enlarged front view of the feeding foot engaging the work. Fig. 6 is a detail view illustrating the co-operation of the fold-determining member and the folder. Fig. 7 is an enlarged perspective view of a portion of the upper feeding foot. Fig. 8 is a sectional view substantially on the line $y-y$ of Fig. 3.

Referring to the drawings, the present improvements are embodied in a folding machine having a work-cylinder 1, from which rises the hollow standard 2 of a tubular overhanging bracket-arm 3 terminating in a head 4. Journaled in suitable bearing provided in the bracket-arm 3 is a main actuating shaft 5, carrying at one end a belt-pulley 6 and at its opposite end a shaft-flange 7 provided on its end face with a crank-pin 8. Pivottally connected with the crank-pin 8 is one end of a link 9 of which the opposite end is connected in like manner with an arm 10 of a bellcrank-lever fulcrumed upon a block 11. The block 11 is rigidly clamped by means of a screw 12 upon a spring-pressed bar 13 mounted for vertical reciprocation in a fixed bushing 14 and an adjustable bushing 15 provided in the

head 4. Interposed between the adjustable bushing 15 and the block 11 is a coil-spring 16 yieldingly urging the bar 13 downwardly until arrested by a cushion-washer 17 surrounding said bar and bearing against the upper end of the bushing 14, said washer being held against upward movement upon said bar by a collar 18 rigidly clamped thereupon. The block 11 has a rear-extension 19 slidingly disposed in a slot 20 provided upon the rear side of the head 4, said extension 19 being adapted to be engaged by a hand lifter-lever 21 to raise the bar 13. The block 11 also has a lateral-extension 22 adapted to be engaged by a treadle-actuated lifter-lever 23 suitably fulcrumed upon the rear side of the bracket-arm 3. The extension 22 is slidingly clamped by the head 24 of a screw against a flat face on the rear side of the machine-arm 3, whereby axial movement of the bar 13 is prevented.

The other arm 25 of the bellcrank-lever 10, 25 is connected by means of a link 26 with the upper end of a feed-bar 27 journaled for vertical reciprocation in aligned apertures provided in the lugs 28 on the forward end of an oscillatory, substantially U-shaped feed-frame 29. At its lower end there is secured upon the feed-bar 27 the shank of a feeding foot 30 having a lower serrated work-engaging face. The forward end of the feeding foot 30 is partially cut away to provide an initial work-engaging toe 31 for a purpose which will hereinafter appear.

The upper limb of the feed-frame 29 is pivotally hung upon a fulcrum-screw 32 threaded into the bracket-arm 3, said feed-frame carrying on its lower limb a conical pivot-stud 33 in vertical alinement with the screw 32 and entering a similarly shaped aperture provided in a detachable fulcrum-plate 34 secured by screws as 35 upon the work-cylinder 1. Suitably secured upon the lower-limb of the feed-frame 29 is the shank 36 of a lower feed-dog 37 preferably having a smooth work-engaging face projecting through a slotted feed-plate 38. Slidingly fitted into suitable under-cut ways provided in the feed-plate 38 is a removable end-cap 39 closing the forward end of the work-cylinder. Secured by means of a screw 40 into a socketed boss 41 of the feed-frame is a pin 42 slidingly fitted into a socketed eccentric-strap 43 embracing an eccentric 44 upon the main-shaft 5, whereby the feed-frame is oscillated about its pivotal support. Any suitable means may be provided for adjusting the eccentric 44 to increase or decrease its effective action upon the feed-frame 29.

From the foregoing it will be understood that rising and falling movements are imparted to the feeding foot 30 from the

main shaft 5 through the bellcrank-lever 10, 25, while work-advancing and return movements are imparted to said feeding foot 30 by means of the oscillatory feed-frame 29. The lower feed-dog 37 is obviously confined to advancing and retracting movements in a single plane, the work being firmly but yieldingly clamped by the spring 16 between the feeding foot 30 and the feed-dog 37 during the advancing movements of the latter.

Secured upon the main-shaft 5 is a belt-pulley 45 connected by means of a belt 46 with a belt-pulley 47 secured upon a rotary folder-actuating shaft 48 disposed within the work-cylinder 1 and journaled in suitable bearings provided in the machine frame. The shaft 48 carries a grooved cam 49, the groove 50 of which is entered by a roller 51 depending from a folder-slide 52. A guideway for the folder-slide 52, confining said slide to right line movements substantially transverse to the direction of feed, is provided by spaced grooved guide-plates as 53 secured by screws as 54 upon a work-cylinder cover-plate 55 fastened by screws 90 as 56 upon the fulcrum-plate 34. The forward end of the cover-plate 55 is preferably clamped upon the work-cylinder 1 by means of an angular clamp-plate 57 secured upon the front side of the work-cylinder by screws as 58.

Adjustably fastened by screws as 59 and elongated slots as 60 upon the folder-slide 52 is the base 61 of a folder 62 having a laterally offset shank 63. The shank 63 terminates in a shoulder 64 beyond which projects the folder 62 having an inclined serrated work-folding face 65. The folder 62 is provided with a downwardly beveled rear surface 66 to provide clearance for the work-engaging movement of the feeding foot, the lower edge 67 of the bevel being inclined to provide an increasing work-engaging surface for the folder as it advances in the folding operation.

The folder 62 acts to bend the work over the free end 68 of a bent fold-determining member 69 adjustably secured upon a lateral ear 70 of an arm 71 by means of screws as 72 and enlarged apertures 73 provided in member 69. The arm 71 is pivoted by means of a screw 74 upon a bracket 75 having elongated slots whereby it is adjustably secured upon the head 4 by screws as 77.

The arm 71 may be swung upon its pivotal support to throw the member 69 into and out of operative position. To this end a latch 78 is pivoted upon the arm 71 by means of a screw 79, said latch having an offset ear 80 adapted to engage a shoulder 81 provided upon the bracket 75, under the action of a spring 82, interposed between

the arm 71 and an ear 84 on the latch 78. An adjustable stop-screw 85 carried by the bracket 75 limits the forward movement of the fold-determining member into operative 5 position, while the ear 84 affords a convenient thumb-piece for tripping the latch 78 to throw said member into an inoperative position retained by any suitable means such as a friction washer. In operation, the 10 fold-determining member 69 is preferably so positioned that its free end 68 is disposed adjacent the toe 31 in the initial work-engaging position of the feeding foot 30, whereby a close association of the parts 15 is possible.

The work comprises a body material *a* to which is secured a corded galloon *b* by a line of stitches *s*. In the operation of the machine, the work is inserted, in the retracted 20 position of the folder 62, under the fold-determining member 69 with the free end 68 of the latter in substantial alinement with the line of galloon-securing stitches *s*, the right side of the work being underneath 25 and overlying the feed-plate 38. The initial end of the work is partially bent or folded by the operator about said free end of the fold-determining member and in the advancing movement of the folder the serrated face 65 thereof, which is inclined 30 downwardly toward the shoulder 64, engages the partially upturned work and doubles it about the fold-determining member with an increasing action due to the inclination 35 of the serrated face 65 and the increasing width of the folder. As the folder 62 is completing its advancing or folding movement, the shoulder 64 bears against the corded or thickened portion of the galloon *b* with a 40 pressure somewhat resiliently opposed by the fold-determining member, thereby insuring a substantially uniform creasing of the body material substantially on the stitch-line *s*. This action is assisted by the 45 fact that the line of stitches in effect acts as a hinge for folding the work. Before the folder 62 begins its retracting movement, the upper feeding-foot 30 has completed 50 its retracting movement and firmly but yieldingly clamps the work upon the feed-dog 37, whereupon the folder 62 is retracted and the work advanced by said clamp-feeding elements. The firm pressure of the 55 feeding foot upon the work causes the previously cemented margin to adhere to the reverse side of the body material. By providing the beveled inclined edge 66, 67, on the folder, the feeding foot may approach more closely to said folder when engaging 60 the work and as this is the only time that the folder and feeding foot simultaneously engage the work, it is possible to turn very sharp curves by reason of the short span of engagement of the work at all times by the several elements.

Having thus set forth the nature of the invention, what I claim herein is—

1. In a folding machine, in combination, folding instrumentalities comprising a member having a fold-determining free 70 end, a folder reciprocated in a right line across the free end of said member to fold the work thereabout, means for reciprocating said folder, and means for advancing the work past said instrumentalities. 75

2. In a folding machine, in combination, folding instrumentalities comprising a fold-determining member, a folder reciprocated in a right line to fold the work about said member, means for reciprocating said folder, and means for advancing the work past 80 said instrumentalities.

3. In a folding machine, in combination, a member having a fold-determining free end, a folder having movements in a right line and provided with a margin-folding face terminating in a fold-edge compressing shoulder at a substantial angle to said face, means for reciprocating said folder to cause its margin-folding face to fold the work-margin about said member, said shoulder acting to compress the fold-edge against the free end of said member, and means for feeding the work past said folder. 85

4. In a folding machine, in combination, 90 a work-support, a folder reciprocable in a right line and having an inclined margin-folding face terminating in a substantially vertical fold-edge compressing shoulder, means for reciprocating said folder, a fold-determining member across which said face is projected, and means for feeding the work past said folder. 95

5. In a folding machine, in combination, 100 a work-support, work-feeding means, a member having a fold-determining free end, a folder movable in a right line across the free end of said member, said folder having a margin-folding face increasing in width 105 from its initial work-engaging end toward the base thereof, and means for reciprocating said folder. 110

6. In a folding machine, in combination, 115 a work-support, work-feeding means including a four-motion upper feeding-foot having a forwardly projecting toe at one side thereof, a member having a fold-determining free end disposed adjacent said toe in the initial work-engaging position of said foot, 120 a folder movable across the free end of said member, and means for reciprocating said folder.

7. In a folding machine, in combination, 125 a work-support, work-feeding means, a fold-determining member, an arm sustaining said member, a supporting bracket, a pivotal support for said arm upon said bracket, a spring-pressed latch carried by said arm for releasably locking said arm in operative position, a folder movable to fold the work- 130

margin across said member, and means for actuating said folder.

8. In a folding machine, in combination, a work support, work-feeding means, a folder determining member, an arm sustaining said member, a bracket supporting said arm, a releasable latch for locking said arm in the operative position of said member,

adjustable means for predetermining the operative position of said arm, a folder movable to fold the work-margin across said member, and means for reciprocating said folder.

In testimony whereof, I have signed my name to this specification.

JOHN C. RINGE.
